CLAIM

The ornamental design for a rotor for a wave energy converter, as shown and described.

DESCRIPTION

FIG. 1 is a perspective view of a rotor for a wave energy converter, showing my new design;
FIG. 2 is a top plan view thereof;
FIG. 3 is a bottom plan view thereof;
FIG. 4 is a right side elevational view thereof;
FIG. 5 is a left side elevational view thereof;
FIG. 6 is a front elevational view thereof; and,
FIG. 7 is a back elevational view thereof.
